CLAIM

The ornamental design for carrier bags for small dogs with accessories, as shown and described.

DESCRIPTION

The patent or application file contains at least one drawing executed in color. Copies of this patent or patent application

publication with color drawing(s) will be provided by the Office upon request and payment of the necessary fee.

1. Carrier bag for small dogs with accessories
2. Carrier bag for small dogs with accessories
3. Carrier bag for small dogs with accessories
- 1.1 : Front
- 1.2 : Perspective top left view
- 1.3 : Top view in half open state (without accessories)
- 1.4 : Unfolded top view (without accessories)
- 1.5 : Unfolded top view (with accessories)
- 1.6 : Unfolded back view
- 1.7 : Perspective folded view
- 1.8 : Partial perspective folded view
- 1.9 : Partial perspective half folded view
- 1.10 : Partial perspective unfolded view
- 1.11 : Partial perspective view
- 1.12 : Partial top view
- 2.1 : Front
- 2.2 : Perspective top left view
- 2.3 : Top view in half open state (without accessories)
- 2.4 : Unfolded top view (without accessories)
- 2.5 : Unfolded top view (with accessories)
- 2.6 : Unfolded back view
- 2.7 : Perspective folded view
- 2.8 : Partial perspective folded view
- 2.9 : Partial perspective half folded view
- 2.10 : Partial perspective unfolded view
- 2.11 : Partial perspective view
- 2.12 : Partial top view
- 3.1 : Front
- 3.2 : Top
- 3.3 : Perspective top left view
- 3.4 : Perspective back view
- 3.5 : Top view in half open state (without accessories)
- 3.6 : Unfolded top view (with accessories)
- 3.7 : Unfolded back view
- 3.8 : Perspective folded view
- 3.9 : Partial perspective folded view
- 3.10 : Partial perspective half folded view
- 3.11 : Partial perspective unfolded view
- 3.12 : Partial perspective view
- 3.13 : Partial top view

The claimed designs have a rectangular shape, one-side external pockets and handles/shoulder straps to wear them;

(Continued)

two-lateral drawstrings allow the closure of the sides; inside each of the bags there are pockets and straps to house accessories, such as a horizontal foldable rigid base, a safety lace for the collar and a safety net; there are buttons and Velcro to attach the pillows for the snout located on the pocket for the rigid base; reproductions 1.8-1.12, 2.8-2.12, 3.9-3.13 are partial views of the accessories (the bases and pillows) shown in reproductions 1.5, 2.5, and 3.6.
